UNITED STATES PATENT OFFICE.

CHARLES J. OPPENHEIM, JR., OF NEW YORK, N. Y.

DISPLAY BOX.

Application filed May 4, 1926. Serial No. 106,611.

This invention relates to display boxes.

The object of the invention is to provide an article of this character designed more particularly for the display of perfumery bottles in which the contained article will be disposed in a manner best calculated to permit of its being handled.

Another object of the invention is to provide a display box of this character in which the contained article can be stored and shipped without breakage and with a great amount of facility and safety.

Other objects will appear as the disclosure progresses. The drawings are intended merely to indicate a possible embodiment of the invention. It is obvious that the actual needs of manufacture may necessitate certain mechanical changes. It is therefore not intended to limit the invention to the embodiment illustrated but rather to define such such limits in the appended claims.

For a more detailed understanding of the invention attention is now called to the drawings in which a preferred embodiment is shown illustrated. In these drawings like parts are designated by like reference characters in all the views.

Fig. 1 is a perspective view of the box.

Fig. 2 is a front view of the box shown in an opened position.

Fig. 3 is a section on line 3—3 of Fig. 2.

Fig. 4 is a front view of the housing for the bottle.

Fig. 5 is a section on line 5—5 of Fig. 4.

Fig. 6 is a section on line 6—6 of Fig. 4.

Fig. 7 is a front view of the backing for the bottle housing.

Fig. 8 is a developed length of the interior wall of the bottle pocket.

Fig. 9 is a perspective view of the reinforcing member of the bottle housing.

Fig. 10 is a section on line 10—10 of Fig. 8.

Referring now to the drawings in detail numeral 1 designates the body of the box and 45 2 the cover hinged thereto by the hinge 3.

Within the box is a bottle housing 4 triangular in cross section and provided with an opening 5 in the front face. The opening is oval in shape with a flat base 6 and inserted therein is a pocket 7 for the insertion of a bottle 8.

The interior walls 9 of the pocket slope outwardly towards the rear thus allowing the bottle to be snugly held in place and prevent its accidentally leaving its position.

Within the pocket is a cushioned backing 10 for the bottle to rest against. The walls 9 of the pocket are preferably made of cardboard in the center numeral 11 with a covering of cloth numeral 12. As noted in Figs. 60 5, 6 the rims of said walls curve outwardly and are provided with a series of slots 13, see Fig. 8. This construction allows the bottle to be resiliently kept in place in the pocket.

Surrounding the exterior of the pocket is 65 a reinforcing member 14. The function of this member is to prevent the sloping wall 15 of the bottle housing from bending inwardly.

As noticed in Fig. 8 one end of the developed length of the wall member 11 is cut straight as at 16 and the opposite end 17 is cut at an angle. Also the score 18 is parallel to the end 17. With this arrangement when the wall member is bent so the ends 16 and 17 meet, the sloping outward sides will be formed as shown in Figs. 5 and 6. Numeral 19 is the base portion of the pocket and corresponds to the flat portion of the opening 5.

Having thus described my invention, what I desire to secure by United States Letters Patent is:

1. In a display box of the character described, a body portion triangular in cross section having a cover attached thereto by a hinge, said cover being triangular in cross section, a bottle housing having a pocket therein within the body portion, said housing being triangular in cross section to conform to the cross section of said body portion, an opening in the front wall of the bottle housing, said opening being oval shaped with a flat base, and a backing in the rear wall of said pocket, the said pocket adapted 85 to snugly retain a bottle in place.

2. In a display box of the character described, a body portion having a cover hinged thereto, a bottle housing adapted to fit in the body portion, said housing being triangular in cross section, an opening in the front face of said housing, said opening being oval in shape with a flat base, a pocket within the interior of said housing, the walls of said pocket sloping outwardly towards the back, outward turned rims of said walls, slits in the said rims, and a backing at the rear wall of said pocket, said pocket arranged to snugly hold a bottle.

3. In a display box of the character de- 110

scribed, a body portion having a hinged cover attached thereto, a bottle housing in said body portion, a pocket in said bottle housing, the walls of said pocket sloping inwardly towards the rear, said walls formed of one piece of material having a straight end and the opposite end cut at an angle, a score parallel to the side cut at an angle adjacent the straight side, and a curved portion at the rim, said rim having slits therein and curving upwardly.

In testimony whereof I affix my signature.

CHARLES J. OPPENHEIM, JR.
